UNITED STATES PATENT OFFICE.

WILLIAM F. MULLER, OF NEW YORK, N. Y.

DESIGN FOR AN INKSTAND.

Specification forming part of Design No. 6,528, dated March 25, 1873.

To all whom it may concern:

Be it known that I, WILLIAM F. MULLER, of the city, county, and State of New York, have invented a new and original Design for an Inkstand, of which the following is a specification:

My design for inkstands is represented in the accompanying drawing by the truncated pyramidal figure with four wide plane sides, A, and four narrow sides or beveled corners,

B, the beveled bottoms and top corners D E, plain top F, and plain ring G rising up from the top around the ink-well.

I claim as my invention—

The design for inkstands, as shown.

WM. F. MULLER.
